SCREEN

Filed June 24, 1925

Inventor:

Clara Dell Smith,
by her father Linley May,
Atty's.

UNITED STATES PATENT OFFICE.

CLARA DELL SMITH, OF READING, MASSACHUSETTS.

SCREEN.

Application filed June 24, 1925. Serial No. 39,164.

To all whom it may concern:

Be it known that I, CLARA DELL SMITH, citizen of the United States, residing at Reading, in the county of Middlesex and 5 State of Massachusetts, have invented new and useful Improvements in Screens, of which the following is a specification.

This invention relates to a screen including a jointed frame composed of two frame 10 members, filling members closing the outer sides of the frame members, and hinges connecting the frame members, the screen being adapted to be opened and closed and to stand vertically on a floor when opened.

15 The object of the invention is to provide a screen thus organized with improved pocket means adapted to securely confine garments and other articles, and with an improved arrangement of shelves adapted to 20 support various articles used in sewing, in such manner that the articles are exposed and conveniently accessible when the screen is opened, and concealed within the screen when the latter is closed.

25 Of the accompanying drawings forming a part of this specification,—

Figure 1 is a perspective view of a screen embodying the invention, showing the screen opened.

30 Figure 2 is a sectional view showing the screen closed.

Figure 3 is a fragmentary perspective view showing a portion of one of the frame members of the screen without the holders.

35 Figure 4 shows in perspective two of the holders before attachment to the screen.

The same reference characters indicate the same parts in all of the figures.

In the drawings, 12, 12 designate two 40 frame members connected by hinges 13 and provided with filling members 14, closing the outer sides of the openings formed by the frame members. The jointed frame members, the hinges, and the filling members, constitute leaves of a screen adapted to be opened as shown by Figure 1, and closed as shown by Figure 2, the screen being adapted to stand vertically on a floor when opened.

50 The filling members are preferably of textile fabric, such as cretonne, silk or tapestry, and are attached by nails 14^a or other suitable fastenings to the outer edges of the strips or bars of which the frame members are made. The frame strips or bars project from the filling members sufficiently to form

the margins of recesses 15 (Figure 3) within the frame members, the backs of the recesses being formed by the filling members. The recesses are sufficiently deep to contain holders fixed to the frame members for holding in the recesses various articles used in sewing. In this instance, said holders include cross bars or shelves 16 fixed to the upright bars of the frame members and extending across the recesses, and upright pins 17 fixed to the shelves, the pins and shelves being adapted to support thread spools. The holders may also include pocket members composed of flexible pocket sides 18 of textile fabric, attached at their lower edges by nails 19 to the bottom strips of the frame members and having free upper edges extending across the recesses, and reinforcing stays 20 engaged with the free edges and attached to the frame members, the stays being preferably composed of helically coiled wire. The sides 18 and the lower end portions of the filling members 14 constitute pockets adapted to hold cloth and small garments. 80 The elastic stays prevent the upper edges of the pocket sides 18 from sagging, and permit them to be bulged outward to a considerable extent by the contents of the pockets, said pockets being of variable capacity and 85 adapted to securely hold considerable accumulations of articles.

To the fixed shelf 16 of one leaf is connected by hinges 22 (Figure 2), a swinging shelf 23 to support various articles used in 90 sewing. The hinges are arranged to permit the swinging shelf to hang vertically and project into the recess in the other leaf when the screen is closed, as shown by Figure 2, and to swing to a horizontal position with 95 its upper surface flush with the upper surface of said fixed shelf, as shown by Figure 1, when the screen is opened, so that the two shelves 16 and 23 constitute collectively a relatively wide and commodious shelf, the 100 shelf 23 being an extension of the shelf 16. The swinging shelf is releasably supported in a horizontal position by a chain 24, secured at one end to the table and adapted to be detachably engaged with a fixed hook 25 on 105 the upper portion of one of the frame members. When the chain is disengaged from the hook, the shelf 23 swings downward and permits the closing of the screen, as shown by Figure 2, the chain depending 110 from the swinging shelf into a recess of the screen. Another shelf 16 may be utilized

to support hooks 26 on which scissors and other articles may be hung.

The frame members may be fastened together by a hasp 27 and a catch 28 when the 5 screen is closed. The upper ends of the frame members are provided with handles 29 permitting the screen to be conveniently transported.

I claim:

- 10 An article of the character stated, comprising: a screen including two similar recessed members hinged together and each having a back and a marginal frame, a shelf within each member extending throughout 15 the width and depth of the recess in the member, the forward edges of said shelves being in contact when the recessed members are closed together, a hook within one mem-

ber above the said shelf therein, a swinging shelf supported by hinges secured to the lower 20 face of the last said shelf, whereby it may hang vertically from said fixed shelf or, when the members are in open relation, extend horizontally therefrom with its upper surface flush with the upper surface of the 25 fixed shelf, said swinging shelf extending throughout the length of the front edge of the fixed shelf, and a chain connected to the swinging shelf and adapted to be engaged with said hook to maintain the swinging 30 shelf in horizontal position, in which it is in alignment with both the fixed shelves.

In testimony whereof I have affixed my signature.

CLARA DELL SMITH.
